UNITED STATES PATENT OFFICE.

RAY G. MYERS, OF CANAL FULTON, OHIO.

DOOR OPENER.

Application filed December 10, 1920. Serial No. 429,725.

To all whom it may concern:

Be it known that I, RAY G. MYERS, a citizen of the United States, residing at Canal Fulton, in the county of Stark and State of Ohio, have invented a new and useful Door Opener, of which the following is a specification.

This invention relates to door opening mechanism for use upon garage doors and the like and has special reference to a fluid operating door opener.

The objects of the invention are to provide a distributing valve in a fluid pressure line which may be easily and quickly operated to allow fluid pressure to enter either end of a cylinder through which a garage door or doors may be opened or closed.

Other objects are the provision of a device of this character which will be extremely simple in construction and which may be easily and readily operated.

With these objects in view the invention consists in the novel construction and arrangement of parts, hereinafter described, illustrated in accompanying drawings, and particularly pointed out in the appended claims, it being understood that various changes in the form, proportions, size and minor details of construction may be made within the scope of the appended claims, without departing from the spirit or sacrificing any of the advantages of the invention.

The invention thus set forth in general terms is illustrated in the accompanying drawings forming part hereof, in which—

Figure 1 is a side elevation of a portion of the wall of a garage or similar building showing the improved door opening apparatus embodying the invention applied thereto; and

Fig. 2, a sectional view through the valve showing portions of the distributing mechanism.

A practical embodiment of the invention is disclosed in the accompanying drawings, forming a part of this specification in which similar numerals of reference indicate corresponding parts throughout the several views.

Although it will be understood that the invention may be applied in various forms the construction shown in the accompanying drawings is chosen for the purpose of illustration. Referring to this construction the numeral 1 indicates generally the portion of a wall of a garage or similar building and

the numerals 2 and 3, a pair of sliding doors of any well known construction, mounted upon a track 4 in the ordinary manner.

A cylinder 5 of a length substantially equal to the width of the two doors is fixedly mounted upon the door 3 by means of brackets or straps 6, a piston 7 being provided within said cylinder, the rod 8 thereof being connected as shown at 9 to the door 2.

A U-shaped bracket 10 is supported upon the wall 1 in a suitable position above the door 3 and supports a pair of nozzles or jets 11 and 12, the inner extremities of which extend within the bracket upon opposite sides thereof. A stop cock 13 or the like is provided in each of the jets for the purpose of regulating the amount of air or other fluid which may be passed therethrough. The jet 11 is connected by means of a flexible hose 14 with the forward end of the cylinder 5, at 15, and the jet 12 is connected by means of a similar hose 16 with the rear end of the cylinder as shown at 17.

A feed pipe 18 extends from a suitable source of compressed air or other fluid and is provided with a depending, slightly flexible pipe 19 upon the lower end of which is supported a double valve casing indicated generally by the numeral 20, said valve casing being suspended within the bracket 10 and between the jets 11 and 12.

A lever 21 is pivoted intermediate its extremities as shown at 22, upon the bracket 10, the upper end of said end having an elongated eye 23 which receives a stud 24 upon the valve casing 20. Cords or other flexible members 25 and 26 are connected to the lower extremity of the lever 21 and disposed in opposite directions, the cord 26 passing over a pulley 27, both of these ends returning to any suitable portion of the garage from which it is desired to operate the doors.

The valve casing 20 is provided with a longitudinal bore 28 extending entirely through the casing, an enlarged chamber 29 being provided in the central portion of the casing and communicating with said longitudinal bore as well as with the vertical bore 30, which communicates with the pipe 19. A valve 31 is slidably mounted in each end portion of the bore 28 and provided with a reduced neck 32 and an enlarged head 33 located within the chamber 29. Suitable means such as the flexible washer 34 engages the reduced portion of

each valve, normally holding said valve in the closed position.

Each of the valves 31 is provided with a longitudinal bore 35 extending through the outer end thereof and communicating at the inner end with a transverse bore 36 located through the reduced neck of the valve. Normally the fluid pressure within the chamber 29 will hold each of the valves 31 in the closed position.

When it is desired to operate the mechanism to open the doors the lever 21 is rocked by means of the cord 25 moving the valve casing toward the jet 12, the adjacent valve 31 being engaged by said jet and forced inwardly allowing fluid pressure to pass from the pipe 19 through said valve and into the jet 12 and then through the hose 16 to the rear end of the cylinder forcing the piston 20 outwardly and opening the doors.

In order to close the doors the cord 26 is pulled, moving the valve casing toward the jet 11, the adjacent valve 31 being opened in the same manner as above described, allowing air to pass through the hose 14 to the forward end of the cylinder.

From the above and an inspection of the accompanying drawing it will be evident that a very simple and effective device is provided by means of which with a double valve carried in a single valve casing adapted for movement into selective engagement with either of the jets which communicate with opposite ends of the cylinder the fluid operated mechanism may be very simply operated.

Although a lever is shown for moving the valve casing into engagement with the jets, it will be understood that any usual and well known means may be provided for shifting the valve casing into engagement with either of the jets and for normally

holding the valve casing in the neutral position. It will also be understood that the device may be applied to a single door as well as to double doors, or to hinged doors as well as to sliding doors, without necessitating any change in the valve shifting mechanism.

I claim:

1. A door operating mechanism of the character described comprising in combination with a fluid cylinder, a jet communicating with each end of said cylinder, a fluid supply line, a valve casing therein, a pair of normally closed valves within said casing, each valve being arranged to be opened by engagement with the adjacent jet and means for moving the valve casing toward either jet to allow fluid from the supply line to pass through said valve and jet to the adjacent end of the cylinder while the other valve remains closed.

2. A door operating mechanism of the character described comprising in combination with a fluid cylinder, a pair of spaced, fixed jets communicating with opposite extremities of said cylinder, a fluid supply line, a valve casing connected to said fluid supply line and suspended between said jets and normally located out of engagement with both jets, a pair of normally closed valves within said casing, each valve being arranged to be opened by engagement with the adjacent jet, while the other valve remains closed, and means for selectively moving said valve casing into engagement with either jet to allow fluid from said supply line to pass into the adjacent end of the cylinder.

In testimony that I claim the above, I have hereunto subscribed my name.

RAY G. MYERS.
